SEWING MACHINE LOOPER MECHANISM

Edward Muecke, Linden, N. J., assignor to The Singer Manufacturing Company, Elizabeth, N. J., a corporation of New Jersey

Application February 23, 1943, Serial No. 476,831

8 Claims. (Cl. 112—200)

This invention relates to looper mechanisms for sewing machines and particularly to looper mechanisms for sewing machines of the two-thread chain-stitch type.

The present invention has for an object to provide an improved mechanism for moving a looper element in a substantially straight path as it enters the needle loops so that the looper may be moved close behind the needles thereby to avoid any possible skipping of the needle loops.

Another object of this invention is to provide an extremely compact looper mechanism of the character referred to with actuating means so constructed and arranged as to permit the same to be lubricated freely and to be operated quietly and smoothly at high speeds.

The novel and characteristic features of this invention are set forth particularly in the appended claims. The invention itself, however, both in structure and in operation, as well as additional objects thereof, will be best understood from the following description:

Fig. 1 is a front elevation, partly in section, of a portion of a sewing machine embodying the present invention.

Fig. 2 is a vertical section view taken substantially along line 2—2 of Fig. 1.

Fig. 3 is a top plan view, partly in section, of the present invention.

Fig. 4 is a vertical section view taken substantially along line 4—4 of Fig. 1.

Fig. 5 is a diagram illustrating the action of a crank and link connection.

Figs. 6 and 7 are diagrams illustrating the paths of movement of two different looper elements as viewed in top plan.

The present invention is shown embodied in a sewing machine of the type disclosed in the United States patent to Albert H. DeVoe, No. 1,100,124, dated June 16, 1914.

Referring more particularly to the drawings the invention is shown as applied to a sewing machine comprising a base 10, feeding mechanism 11, cloth-presser 12 and a needle-bar 13 which latter carries the needles 14. Journalled in bearings 15 and 16 carried by the base 10, is a main or actuating shaft 17 which is rotated in a manner common to sewing machines.

The improved looper mechanism comprises one or more loopers 18 secured by means of a screw 19 upon a substantially vertically disposed looper-carrier 20 provided at the lower portion thereof with a horizontally disposed tubular sleeve or support 21 which is slidably mounted upon a stationary fulcrum arbor 22. Projecting upwardly from the frame 10 is a bearing block 23 provided with an aperture 24 for the purpose of receiving the forward portion of the arbor 22 of which the rear portion is pointed, as at 25, and mounted within a seat 26 formed in the base 10. This arbor is disposed transversely of the main shaft

17 and it is rigidly secured in position by means of a set screw 27.

Adjustably clamped upon the sleeve 21 by means of screws 28 is a split collar 29 from one side of which projects an arm 30 carrying a ball 31 provided with a steady-pin 32. This ball 31 is received within the socket portion 33 formed on the lower end of a vertical pitman 34 of which the strap portion 34' surrounds an eccentric 35 fastened upon the shaft 17. To the lower portion of this pitman 34 there is secured by means of a screw 36 a slotted guide-block 37 which coats with the pin 32 to steady the pitman and prevent it from wobbling on the eccentric 35. Rotation of the shaft 17 will oscillate, through the medium of the eccentric 35, pitman 34, and arm 30, the looper 28 back and forth about the fulcrum arbor 22, thus to produce the loop-seizing movements of the looper 18. The path of loop-seizing movements lies in a direction across the line of seam-formation.

Sidewise or needle-avoiding movements are imparted to the looper from an eccentric 38 secured upon the shaft 17. Embracing the eccentric 38 is a strap 39 of a short horizontal pitman 40 carrying crosswise of one end thereof a pin 41 which is secured thereto by means of a set screw 42. The opposite end portions of the pin 41 are embraced by the spaced arms 43 of a flanged bolt 44 which is threaded into a horizontal guide-rod 45. This guide-rod 45 is disposed in parallel relation with the arbor 22 and it is slidably received within an apertured bearing 46 which is secured within the block 23 by means of set screws 47.

Clamped between the flanged portion 48 of the bolt 44 and one end of the guide-rod 45 is a shouldered collar 49 which is slidably received within an arcuate slot 50 formed in the looper-carrier 20. Although the collar 49 is rigidly clamped between the rod 45 and the flange 48 enough clearance is provided between the collar and the flange to insure that the looper-carrier may slide relative thereto.

Rotation of the eccentric 38 will reciprocate the guide-rod 45 in the direction of seam formation and it will thereby impart the sidewise movements to the looper-carrier 20 which will remain vertically disposed at all times as its sleeve 21 may slide back and forth longitudinally of the arbor 22 simultaneously with the rocking movement of the sleeve. Rotation of the shaft 17 will impart, through the medium of eccentrics 35 and 38 and their accompanying mechanisms, both the loop-seizing and the sidewise movements to the looper element 18.

Thus the sleeve 21 and the guide-rod 45 comprise a pair of spaced parallel members which are supported to slide transversely of the main-shaft 17, the looper-carrier 20 being rigidly

mounted upon the sleeve 21 and being slidingly connected with the guide-rod 45.

A usual type of looper mechanism, when viewed in top plan view, imparts an elliptical shaped path of movement to its looper, which path has the major axis thereof usually disposed substantially transversely of the direction of seam formation. Fig. 7 illustrates such a path of looper movement. Whenever such a looper mechanism is employed in a sewing machine having a plurality of needles, difficulty is experienced for the reason that as the spacing between the needles is varied, to meet the divers sewing conditions, the relative distances between the needles and the looper path are also changed. Of course if the distance between the needle and the looper path became very great the looper will be unable to seize the needle loop when the looper passes behind the needle. This condition is illustrated in Fig. 7 which shows that needle 14' by being spaced from needles 14 is consequently shifted away from the looper path 58. Therefore, the use of a looper having an elliptical path of movement, as shown in Fig. 7, limits the spacing between the needles to only the relatively narrow gauges.

The present mechanism obviates the above described difficulty as its looper traverses a path, as viewed in top plan, in the form of a flattened ellipse, the flattened portion of the ellipse representing the loop-seizing portion of the looper movement. This path of movement is illustrated in Fig. 6 and from this figure it may readily be understood that the spacing between the needles 14 may be varied within wide limits without appreciably affecting the distance between the needles and the path of looper movement. Therefore, the needles of the present machine may be set for wide gauge stitching without the danger of the looper skipping the needle loops.

This flattened ellipse is produced by utilizing an eccentric 38 and an extremely short length pitman 40 for imparting the sidewise movements to the looper. Fig. 5 illustrates the action of the eccentric 38 and the short pitman 40 by showing the paths of movement of an equivalent mechanism, namely a rotary crank 51 and a link 52 one end of which is confined to straight line movement. Fig. 5 is drawn on a scale substantially three times that of the Fig. 4 for the purpose of better illustration.

As the crank 51 rotates in a clockwise direction from point 53 to point 54 the free end of the link 52 moves from point 55 to point 56 and return which movement represents a substantially greater distance than that covered by the free end of the link when it moves from point 55 to point 57 and return as the crank rotates clockwise from point 54 to point 53. If the link 52 was infinitely long the distance B would equal distance A, and as the length of the link 52 becomes shorter relative to crank 51 the difference between distances A and B becomes proportionately greater. Therefore, it is advantageous to employ a rotary eccentric and a relatively short pitman for imparting the sidewise movements to a looper as the movements derived therefrom, when combined with the back and forth movements of the looper, produce an elliptical path of which one side is flattened. Fig. 6 illustrates by line 58 the top plan view of the path of movement of the present looper element 18. When the eccentric 38 is in a dead center position the pitman 40 is aligned with the guide-rod 45.

The applicant realizes that he is not the first to employ an eccentric and short pitman mechanism for imparting the sidewise movements to a looper but he does believe himself to be the first inventor of the present compact and simple mechanism which permits the eccentric and short pitman to be most effectively employed. Fig. 3 well illustrates the compactness of the present looper-actuating unit.

Due to the fact that the present mechanism has been designed for high-speed operation provision has been made for fully lubricating the same. Lubricant is delivered, from a source not herein shown, to pipes 59 and 60 from which pipes it is distributed to all of the pertinent relatively moving surfaces of the mechanism. As best shown in Fig. 4, pipe 60 communicates with a vertical duct 61 formed in the block 23 and bearing 46, and intermittently aligned with duct 61 is a vertically disposed duct 62 formed in the guide-rod 45 for the purpose of permitting lubricant to flow into duct 63 which terminates in a horizontal passageway 64 formed in the fulcrum arbor 22. In Fig. 1 there is shown ducts 65 radially projecting from the passageway 64 for the purpose of distributing lubricant to the relatively moving surfaces of the arbor 22 and the sleeve 21.

As illustrated in Figs. 1 and 3, pipe 59 communicates with the horizontally disposed duct 66 formed in the shaft 17 for the purpose of delivering lubricant to the radially disposed ducts 67 which are formed in the shaft 17 and the eccentric 35 thereby to lubricate the surfaces of the eccentric 35 and pitman strap 34'. As best shown in Figs. 3 and 4 the duct 66 continues within the shaft 17 beyond the eccentric 35 to join a radial duct 68 formed in the shaft 17 and the eccentric 38 for the purpose of delivering lubricant to the interengaging surfaces between the eccentric 38 and the pitman strap 39.

Intermittently connected with the radial ducts 67 is a vertical duct 69 located in the pitman 34 and adapted to deliver lubricant to the ball 31 and socket 33. A portion of this lubricant will find its way to the angular shaped duct 70 which leads to interengaging surfaces of the arbor 22 and sleeve 21. Thus it may be seen that the present device is fully lubricated.

Having thus set forth the nature of the invention what I claim herein is:

1. In a sewing machine looper-actuating mechanism having a main-shaft, an actuating member and an eccentric mounted upon said main-shaft, an arbor disposed transversely of said main-shaft, a looper-carrier slidably and pivotally mounted upon said arbor, a looper mounted upon said carrier and having a blade confined to parallelism with a fixed plane, and a connection between said actuating member and said looper-carrier for rocking the latter about said arbor; the improvement which comprises the provision of a pitman of which one end is connected directly with said eccentric, the body of said pitman being disposed, when in a dead center position in parallelism with said arbor and the other end thereof being connected to said looper-carrier for sliding the same lengthwise of said arbor.

2. In a sewing machine looper-actuating mechanism having a main-shaft, an actuating member and an eccentric mounted upon said main-shaft, an arbor disposed transversely of said main-shaft, a looper-carrier slidably and pivotally mounted upon said arbor, a looper mounted

upon said carrier and having a blade confined to parallelism with a fixed plane, and a connection between said actuating member and said looper-carrier for rocking the latter about said arbor; the improvement which comprises the provision of means slidably connected with said looper-carrier and confined to straight line movement parallel to said arbor, and a pitman of which one end is connected directly with said eccentric, the body of said pitman being disposed, when in a dead center position, in parallelism with said arbor and the other end thereof being pivotally connected with said means for sliding said looper-carrier lengthwise of said arbor.

3. In a sewing machine looper-actuating mechanism having a main-shaft, an actuating member and an eccentric mounted upon said main-shaft, a support mounted to slide lengthwise of itself in a direction transversely of said main-shaft, a looper-carrier rigidly mounted upon said support, and a connection between said actuating member and said looper-carrier for rocking the latter about the longitudinal axis of said support; the improvement which comprises the provision of a guide member whose longitudinal axis is constantly parallel to that of said support and lies in a plane containing the axis of said main-shaft, said guide member being slidably connected with said looper-carrier, and a pitman of which one end is connected directly with said eccentric, the body of said pitman being disposed, when in a dead center position, in alignment with said guide member and the other end thereof being pivotally connected with said guide member for sliding the same endwise of itself.

4. A looper-actuating mechanism for sewing machines, comprising, a main-shaft, a pair of eccentrics mounted on said main-shaft, a pair of spaced parallel members supported to slide transversely of said main-shaft, a looper-carrier rigidly mounted upon a first one of said parallel members, said looper-carrier being slidably connected with a second one of said parallel members, a pitman embracing one of said eccentrics and being connected with said first one of said parallel members for rocking the same about its longitudinal axis, and a second pitman embracing the other one of said eccentrics and being connected to said second one of said parallel members for sliding the same lengthwise of itself.

5. In a sewing machine looper-actuating mechanism having a main-shaft, a looper having a loop-seizing blade, a looper-carrier movable in two directions respectively lengthwise and crosswise of said blade and confined against movement in all other directions, a fixed supporting member for said looper-carrier arranged transversely of and at one side of said main-shaft, and means actuated by said main-shaft for rocking said looper-carrier about the transverse axis of said fixed supporting member; the improvement which comprises the provision of a guide member whose longitudinal axis is parallel to that of said supporting member and lies in a plane containing the axis of said main-shaft, said guide member being slidably connected with said looper-carrier, and means actuated by said main-shaft and connected with said guide member for

shifting said looper-carrier longitudinally of said guide member.

6. In a sewing machine looper-actuating mechanism having a main-shaft, an actuating member and an eccentric mounted upon said main-shaft, a support mounted to have rocking movements about and sliding movements lengthwise of an axis disposed transversely and at one side of said main-shaft, a looper-carrier rigidly mounted upon said support, and a connection between said actuating member and said support for rocking the same about the axis of said support for imparting loop-seizing movements to said looper-carrier; the improvement which comprises the provision of a guide-rod whose longitudinal axis is disposed transversely of and lies in a plane containing the axis of said main-shaft, a collar carried by one end of said guide-rod and slidably embracing said looper-carrier so that the latter may shift transversely of said guide-rod, and a pitman of which one end is connected directly with said eccentric, the other end being connected to said collar for shifting said guide-rod endwise of itself, thereby imparting sidewise movements to said looper-carrier.

7. In a sewing machine looper-actuating mechanism having a main-shaft, a looper having a loop-seizing blade, a looper-carrier movable in two directions respectively lengthwise and crosswise of said blade and confined against movement in all other directions, a fixed supporting member for said looper-carrier arranged transversely of and at one side of said main-shaft, and means actuated by said main-shaft for rocking said looper-carrier about the transverse axis of said fixed supporting member; the improvement which comprises the provision of a guide-rod whose longitudinal axis is disposed transversely of and lies in a plane containing the axis of said main-shaft, a collar carried by one end of said guide-rod and slidably embracing said looper-carrier, an eccentric mounted upon said main-shaft, and a pitman of which one end is connected directly with said eccentric, the body of said pitman being disposed, when in a dead center position, in alignment with said guide-rod, the other end thereof being pivotally connected with said collar.

8. A looper-actuating mechanism for sewing machines, comprising, a main-shaft, a pair of eccentrics mounted upon said main-shaft, a pair of spaced parallel members supported to slide transversely of said main-shaft, a first one of said members having its longitudinal axis lying in the plane containing the axis of the main-shaft, a looper-carrier rigidly mounted upon a second one of said parallel members and having an elongated slot provided therein, a pitman embracing one of said eccentrics and being connected with said second member for rocking the same about its longitudinal axis, a collar rigidly secured upon one end of said first member, said collar being received within said elongated slot and slidably embracing the opposite sides of said looper-carrier, and a pitman embracing the other one of said pair of eccentrics and being pivotally connected to said collar, the body of said pitman being disposed, when in a dead center position, in alignment with said second member.

EDWARD MUECKE.
